(57) **CLAIM**

The ornamental design for a grill ornament, as shown and described.

DESCRIPTION

FIG. 1 shows a perspective view of the grill ornament.
FIG. 2 shows a front elevation view thereof.

FIG. 3 shows a rear elevation view thereof.

FIG. 4 shows a right side elevation view thereof.

FIG. 5 shows a left side elevation view thereof.

FIG. 6 shows a top plan view thereof; and,

FIG. 7 shows a bottom plan view thereof.

In the drawings, the broken lines depict environmental subject matter only and form no part of the claimed design.

1 Claim, 4 Drawing Sheets
